CLAIM

The ornamental design for a rotating strap, as shown and described.

DESCRIPTION

FIG. 1 is a top, front and right side perspective view of a rotating strap showing my new design;

FIG. 2 is a top, rear and left side perspective thereof;

FIG. 3 is a perspective view thereof, showing the rotating strap in the alternate state.

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view thereof, taken from encircled portion 10 in FIG. 1; and,

FIG. 11 is an enlarged view thereof, taken from encircled portion 11 in FIG. 1.

The broken lines in the drawings represent portions of the rotating strap and form no part of the claimed design. The other broken lines showing text represent indicia and form no part of the claimed design. The dot-dash broken lines in FIGS. 1, 10, and 11 are included to show a partially enlarged view only and form no part of the claimed design.
